(57) **CLAIM**

The ornamental design for a alcohol roll-on dispenser, as shown and described.

DESCRIPTION

FIG. 1 is an exploded front elevational view of the alcohol roll-on dispenser of the present invention;

FIG. 2 is an exploded rear elevational view of the alcohol roll-on dispenser of FIG. 1;

FIG. 3 is an exploded right side elevational view of the alcohol roll-on dispenser of FIG. 1;

FIG. 4 is an exploded left side elevational view of the alcohol roll-on dispenser of FIG. 1;

FIG. 5 is an exploded top plan view of the alcohol roll-on dispenser of FIG. 1; and,

FIG. 6 is a top, rear, perspective in an alternate position (cap attached).

The bottom of the alcohol roll-on dispenser is plain and unornamented and forms no part of the claimed design.
